UNITED STATES PATENT OFFICE

161,913

GARDEN RULE AND SEED TRAY

Joseph A. Fraim, Norfolk, Va.

Application September 18, 1950, Serial No. 12,244

Term of patent 3½ years

(Cl. D52—1)

To all whom it may concern:

Be it known that I, Joseph A. Fraim, a citizen of the United States, residing at Norfolk, in the county of Norfolk and State of Virginia, have invented a new, original, and ornamental Design for a Garden Rule and Seed Tray, of which the following is a specification, reference being had to the accompanying drawing, forming part thereof.

Figure 1 is a plan view of a garden rule and seed tray, embodying my design.

Fig. 2 is an edge view of the garden rule and seed tray.

Fig. 3 is a bottom view of the garden rule and seed tray.

Fig. 4 is a sectional view taken on line 2—2 of Fig. 1.

The dominant features of the design are shown in full lines.

I claim:

The ornamental design for a garden rule and seed tray, as shown and described.

JOSEPH A. FRAIM.
